Primary Examiner — Marie D. Fast Horse

(74) Attorney, Agent, or Firm — Crestron Electronics, Inc.

(57) **CLAIM**

The ornamental design for a video phone, as shown and described.

DESCRIPTION

FIG. 1 is a front isometric view of a video phone showing our new design in a position of use with a handset removed from a base;

FIG. 2 is a rear isometric view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is another front isometric view of the video phone of FIG. 1 shown in an alternate position of use with the handset docked on the base; and,

FIG. 10 is another right side elevation view thereof. The broken lines in the drawings depict parts of the video phone that form no part of the claim.

1 Claim, 10 Drawing Sheets
